UNITED STATES PATENT OFFICE.

DUDLEY D. WALKER, OF OGDEN, NEW YORK.

WINDMILL.

SPECIFICATION forming part of Letters Patent No. 365,955, dated July 5, 1887.

Application filed April 23, 1887. Serial No. 235,850. (No model.)

To all whom it may concern:

Be it known that I, DUDLEY D. WALKER, of Ogden, in the county of Monroe and State of New York, have invented a new and useful 5 Improvement in Windmills, which improvement is fully set forth in the following specification, and shown in the accompanying drawings.

The object of my invention is to produce an 10 improved windmill, the improvement relating mainly to the wheel, and consisting in the manner of bracing and supporting the blades and arms carrying them, to the end that the wheel shall be light and sensitive to the action of the winds.

Referring to the drawings, Figure 1 is a front elevation of the improved wheel, a part of one 15 of the blades being broken away; Fig. 2, a side elevation of the same with connected parts, seen as indicated by arrow *x* in Fig. 1, parts being broken away and omitted, one of the 20 blades and parts attached being shown in dotted lines; Fig. 3, a view of the parts, seen as indicated by arrow *y* in Fig. 2, the arms being broken away at their outer ends and the 25 blades and other parts omitted; Fig. 4, drawn to a larger scale, shows the manner of attaching the braces for the arms, the latter, with the flange, being in part broken away and sectioned, the figure being seen in the direction 30 in which Fig. 2 is seen; and Fig. 5, seen in the direction in which Fig. 2 is seen, better shows the manner in which the secondary ties connect the band with the main braces of the 35 blades, the band and contiguous blade being sectioned through the openings through which the tie passes.

Referring to the parts, A is the wheel, B the frame or support therefor, and C the vane, 40 which frame and vane are of common kind.

a is the shaft of the wheel, resting in a bearing, *b*, of the frame and provided with a crank, *c*, at its inner end.

d is a hub secured to the shaft, from which 45 arms *e* extend outward to hold blades *f*, which blades are secured rigidly to the arms by bolts at *g*.

To the crank *c* is attached a pitman, *h*, which connects with a vertically-moving pump rod,

i, having bearings in the frame at *c'* and *d'*. 50 Said crank, pitman, and pump-rod being of common kind, are not herein further described. A rod, *k*, is passed around the outer ends of the blades and secured rigidly to the latter, forming a peripheral ring for the purpose of 55 strengthening said blades.

l is a series of main tie-rods for the blades, there being one for each blade, each tie-rod having one end made fast to the forward edge of a blade and extending in front thereof to 60 the inner bolt *g* of the nearest adjacent or succeeding arm *e* and in rear thereof.

n is a series of secondary short ties for the blades, each being joined at *o* to a main brace *l* at one end and to the overhanging corner *p* 65 of the nearest blade at the other end.

r is another series of secondary ties joining the braces *l* with the respective rear edges of the blades.

s is a circular concentric band placed against 70 the rear edges of the blades about midway of the length of the latter, to which band the rear ends of the ties *r* are secured, preferably by being passed through said band with nuts on the back side thereof. The shaft *a* is made 75 to extend some distance in front of the wheel and provided at its end with a rigid flange, *t*, from which braces *u* extend obliquely back to the respective arms *e*, to which they are joined at points just within the blades, which 80 braces I prefer to join to said arms and flange by screw-nuts *a'*, as shown. The peripheral ring *k*, band *s*, and the ties and braces *l*, *n*, *r*, and *u* render the wheel stiff and strong for the purpose of withstanding the pressure of 85 the wind, while all parts of the wheel are made very light, so as to have little inertia, for the purpose of making the wheel sensitive to currents of air, this being mainly the object aimed at in my invention. The hub of 90 the wheel is formed with a cylindrical part, *b'*, to which a brake of simple form is to be applied to control in part the movements of the wheel.

What I claim as my invention is— 95
In combination with the crank-shaft of a windmill, a wheel having a hub secured to said shaft, with radial arms extending from

said hub, inclined blades to be acted upon by the wind, secured rigidly to said arms, a peripheral ring secured to the ends of said blades, a main tie-rod joining the forward edge of 5 each of said blades with said arm following it, secondary ties *n* and *r*, connecting said main tie-rod with the two adjacent blades, re-

spectively, and a band at the rear of said blades held by said secondary ties *r*, substantially as shown and described.

DUDLEY D. WALKER.
